(57) **CLAIM**

I claim the ornamental design for a pad for door stopper attachment, as shown and described.

DESCRIPTION

FIG. 1 is a perspective view of a pad for door stopper attachment, showing my new design;

FIG. 2 is a front elevation view thereof;

FIG. 3 is a rear elevation view thereof;

FIG. 4 is a left-side elevation view thereof, the right-side elevation view being a mirror image thereof, therefore not shown;

FIG. 5 is a top plan view thereof; and,

FIG. 6 is a bottom plan view thereof.

The broken lines in the drawings depict portions of the pad for door stopper attachment that form no part of the claimed design.
